UNITED STATES PATENT OFFICE.

THOMAS E. PRAY, OF CHICAGO, ILLINOIS, ASSIGNOR TO GOODMAN MANUFACTURING COMPANY, OF CHICAGO, ILLINOIS, A CORPORATION OF ILLINOIS.

DRAFT DEVICE FOR MINING MACHINES.

1,411,932.

Specification of Letters Patent.

Patented Apr. 4, 1922.

Application filed November 22, 1920. Serial No. 425,655.

To all whom it may concern:

Be it known that I, THOMAS E. PRAY, a citizen of the United States, residing at Chicago, in the county of Cook and State of Illinois, have invented a Draft Device for Mining Machines, of which the following is a specification.

This invention relates to improvements in draft devices for coal mining machines of the class adapted to be moved along the face of a mine wall to cut a horizontal kerf thereunder, and has for its principal object, to provide an improved means associated with a draft mechanism for controlling the height 15 of the kerf.

My invention will best be understood by referring to the accompanying drawings, in which—

Figure 1 is a plan view of a mining machine provided with a preferred form of my invention.

Figure 2 is a side view of the same machine.

Figure 3 is a vertical cross section taken 25 on line 3—3 of Figure 1, and showing the draft control device in enlarged detail.

Figure 4 is a vertical cross section similar to Figure 3, but showing the sheave in raised position.

30 Mining machines of the class shown herein, to illustrate the use of my invention, usually have as common features, a body portion A adapted to rest on the mine floor, and a cutting element B extending longitudinally from the body portion suitable for cutting the kerf. The cutting element may comprise any suitable device for this purpose, as for instance a cutter bar 1, carrying a movable cutter chain as indicated by the 40 dotted lines in Figure 1. Such machines are provided with a motor mounted on the body portion A having driving connection with the cutting mechanism and also having driving connection with draft device for moving 45 the machine during its cutting operation. In the particular form of mining machine illustrated, the draft device comprises a cable drum 2, preferably mounted on the advance side of the mining machine, and rearwardly of the front end 3 of the body portion A. A flexible cable 4 or its equivalent, which is termed the feed rope, is adapted to be wound on the drum and is led about a sheave 5 and anchored at a distance from the 55 machine.

In the operation of machines of the class described, it is often necessary to follow a rolling or unlevel mine floor in forming a kerf, and while so doing, the cutter bar 1 has a tendency to travel in the natural plane 60 predetermined by its position when its initial cut is made under the coal. Furthermore, it sometimes occurs that the cutter bar becomes deflected upwardly from the mine floor as it is cutting, which deflection may be due to several causes, as for instance, on account of uneven hardness of the material to be cut, or on account of uneven degree of sharpness of the cutter bits which make up the cutter chain. 70

In the present invention, I provide means for controlling the height of the kerf by means of the adjustment in height of the sheave 5 about which the draft device 4 is engaged. This sheave has heretofore been 75 similarly positioned in machines of this class, but has been fixed on the machine substantially in the horizontal plane of movement of the cutter chain about the cutter bar 1. In the novel device embodying the present 80 invention, however, this sheave is rotatably mounted on a sleeve 6, having vertical adjustment on a spindle 7 extending upwardly from a boss 8 formed in the base plate 9 of the machine body. The sleeve 6 has a 85 threaded bolt 10 extending axially through its upper end 11 and engaging the upper end of said spindle. An inset portion 7a of hardened metal is preferably provided on the upper end of said spindle to afford a 90 bearing at this point. The upper end 11 of the sleeve 6 extends through a supporting bracket 12, attached to the side of the machine frame by any suitable means such as bolts 13, 13. Means are provided for maintaining said sleeve 6 against rotation, which may comprise a key 14 seated in the spindle 7 and engaging in an oppositely disposed keyway or slot 15, extending longitudinally of the sleeve, or any other equivalent device 95 100 for this purpose.

In the arrangement illustrated, it will be observed that the sheave and the mechanism associated therewith is mounted on an axis inclined toward the rear of the machine. 105 This arrangement is provided so as to afford a substantially straight pull from the sheave to the bottom of the draft drum 2 which, in the machine illustrated, is below the horizontal plane of movement of the cutter 110

chain. It is manifest, however, that the sheave axis may be varied somewhat from the position shown depending upon the arrangement of the draft rope 2, and its associated operating mechanism.

The use and operation of my device is as follows: When the sleeve 6, and the sheave 5 carried thereby, are in their lowermost positions as illustrated in Figure 2, the sheave 10 is substantially in horizontal alignment with the cutter bar. The draft rope 2 is trained about said sheave and is anchored at a distance from the machine preferably at or near the floor of the mine in the usual manner. The draft means thus advances the machine laterally along the mine wall as the cutter bar forms the kerf. The body portion A of machines of this type has a relatively narrow supporting face, so that said machine body will tend to follow uneven or rolling floor. But as has been before suggested, the cutter bar has a tendency to follow in a uniform plane determined by its initial position in the coal. Consequently, when the machine is moved along an uneven or rolling surface, the cutter bar will have either a tendency to "dig in," i. e., cut down towards the floor, or to "ride up," i. e., cut at an angle away from the floor. The tendency to "dig in" is readily controlled by the supporting face of the machine body, which rests on the mine floor and guides the cutter bar upwardly to counteract the "digging in" tendency. In case the cutter bar starts to "ride up" the mine wall, however, the weight of the machine body has been found ineffectual in keeping the cutter bar at its normal height from the floor. When this occurs, the forward end of the machine is raised with the cutter-bar, thereby causing an unnecessary strain on the machine, and its working parts, as well as forming an uneven kerf-height. With the present invention, the machine may be returned to its normal cutting plane by manipulating the screw 10 by any suitable means such as a wrench so as to raise the sheave 5 to some such position as shown in Figure 4. The draft rope 2 then exerts a pull from a point 60 above the horizontal center line of the cutter chain, thereby tending to deflect the cutter bar downwardly. This manipulation of the bolt 10 may take place without loosening or slackening the draft rope, and if desired, 65 while the machine is moving. The sheave

may be adjusted to any height until it becomes effective for the purpose of returning the cutting element to its normal height above the mine floor, and thereafter, the sheave may be again returned to its normal cutting position by reversing the action of the screw 10. Since the draft rope is usually anchored at the floor of the mine, and the sheave is also raised from its normal line of tangency with respect to the cable drum, 65 a downward thrust is exerted upon the sheave and the latter will resume its normal position automatically.

I claim as my invention:

1. In a mining machine having suitable 70 mechanism for cutting a continuous kerf, in combination, a flexible draft means, a spindle mounted on the machine frame, a sleeve member mounted on said spindle, a guide carried by said sleeve, and adapted to 75 be engaged by said draft means, a screw device affording relative longitudinal movement between said spindle and said sleeve, and means preventing the rotation of said sleeve on said spindle. 80

2. In a mining machine having suitable 85 mechanism for cutting a continuous kerf, in combination, a flexible draft means, a spindle mounted on the machine frame, a sleeve mounted on said spindle, a sheave rotatably 90 mounted on said sleeve and adapted to be engaged by said draft means, a screw device having threaded engagement with said sleeve and adapted to coact with said spindle to afford relative longitudinal movement between the two last named elements, and means preventing the rotation of said sleeve on said spindle. 95

3. In a mining machine having suitable 100 mechanism for cutting a continuous kerf, in combination, a flexible draft means, a spindle mounted on the machine frame, a sleeve mounted on said spindle, a sheave rotatably 105 mounted on said sleeve and adapted to be engaged by said draft means, a screw device having threaded engagement with said sleeve and adapted to coact with said spindle to afford relative longitudinal movement between the last named elements, supporting means engaging the exterior of said sleeve, and means preventing the rotation of said sleeve on said spindle. 110

Signed at Chicago, Illinois, this 19th day of November, 1920.

THOMAS E. PRAY.
